Application May 14, 1959, Serial No. 55,910

Term of patent 14 years

(Cl. D81—7)

FIG. 1.

FIG. 2.

FIG. 3.

The rear of the fireplace is plain and the side not shown is a mirror image of the one shown. It is to be understood that the screen fragmentarily shown in Figures 2 and 4 covers the entire opening.

I claim:

The ornamental design for fireplace, as shown and described.
